UNITED STATES PATENT OFFICE.

CHARLES F. SCHLOSSER, OF BROOKLYN, NEW YORK.

COMMODITY CONTAINER.

1,424,682.

Specification of Letters Patent. Patented Aug. 1, 1922.

Application filed May 31, 1921. Serial No. 473,886.

To all whom it may concern:

Be it known that I, CHARLES F. SCHLOSSER, a citizen of the United States, residing at Brooklyn, in the county of New York and State of New York, have invented new and useful Improvements in Commodity Containers, of which the following is a specification.

This invention relates to chests or holders 10 or containers.

More particularly the invention relates to holders for numerous commodities such as coffee, tea, sugar, salt, pepper and spices, and so forth.

Some of the objects of the present invention are: to produce a holder for numerous commodities which embodies means for discharging any part of either of the commodities at will; to produce a simple and inexpensive holder of the character mentioned which may be of convenient use to housewives or chefs, and useful in restaurants. With these and other objects in view the invention resides in the particular construction 25 and the relative arrangement of parts hereinafter more fully described and illustrated in the accompanying drawings, in which:

Figure 1 is a top plan view of the holder with the cover thereof removed.

Figure 2 is a sectional view taken on the line 2—2, Figure 1.

Figure 3 is a horizontal sectional view taken on the line 3—3, Figure 2.

Figure 4 is a horizontal sectional view 35 taken on the line 4—4, Figure 2.

Figure 5 is an elevation of a part of the body member of the holder.

Figures 6 and 7 are detail views.

Referring now more particularly to the 40 several views of the drawing for the details, it will be apparent that, the holder of the present invention will include a holder-proper 10 which is rotatably mounted on a base having the necessary axis for the holder-proper 10. The holder-proper 10 includes a 45 hollow, preferably cylindrical, body-member 11. The body-member 11 is divided into a plurality of series of commodity receiving receptacles, there being an inner, preferably 50 annular series 12 and an outer annular series 13. The receptacles are formed by the employment of plates 14 and 15; attaching members 16, 17 and 18; and a post 19. The plates 14 extend radially from the post 19 55 and are held in place by the attaching members 16 and 17. The members 16 and 17

cross-sectionally are U-shape to provide spaced plates to which the ends of the plates 14 are attached. The members 16 are attached to the post 19 in any suitable manner, 60 and the members 17 are attached to the wall 20 of the body-member 11 likewise. The plates 15 are arranged endwise between the plates 14 and are held in place by the attaching members 18. Each of the plates 14 has 65 a plurality of slots 21 therein. Each of the attaching members 18 consists of a pair of plates 22 each of which is cut or formed to define portions 23 which are insertable in particular slots 21, and which portions engage the plates 14 to which they are connected. The lower end of the body-member 11 is closed by a bottom-member 24 which has a plurality of series of openings therein so arranged as to provide a discharge opening for each of the receptacles 12 and 13. Each of the openings 25 of the receptacles 12 has arranged with relation thereto, for movement, to obstructing and unobstructing positions, a member 26, which is pivotally secured as at 27 to the bottom-member 24. Each of the members 26 has an enlarged portion 28, which, according to the disposition of the said members is movable relatively with respect to its particular opening 70 75 80

25. Each member 26 is also formed with a manipulating handle 29 which extends through and beyond the wall of the body-member 11. Each of the openings 30 of the receptacles 13 has arranged with relation thereto, for movement, to obstructing and unobstructing positions, a member 31, which is pivotally secured as at 32 to the underside of the bottom-member 24. Each member 31 90 comprises an enlarged part 33 and a manipulating handle 34. According to the arrangement of the members 31 the enlarged part 33 of each member, is movable with respect to its related opening 30. An annular member 35 is attached to the body-member 11 and the said member 35 has a series of slots 36 and a series of slots 37 therein. The handles 29 of the members 26 extend through the slots 36 and the handles 34 of the members 31 extend through the slots 37. The end 105 walls of the said slots limit the members 26 and 31 in their movements. The post 19 is hollow and is attached to the bottom-member 24. A spindle 38 is received by the hollow post 19. The lower end of the spindle 110 is screw threaded as at 39 for threading engagement with a screw threaded bore 40 in

the base 41. The upper end of the spindle 38 has a screw threaded bore 42 therein to receive a headed screw 43. The head of the screw 43 lies against the top of the post 19 5 and thus holds the parts together. The body-member 11 is closed at the top by a cover 44 which has a suitable handle or handles.

From the foregoing it will be obvious that 10 the holder of the present invention will embody a multiplicity of receptacles in which there may be placed different commodities; that the discharge of a particular commodity is accomplished by the manipulation 15 of a particular control member; that the particular control member may be brought into convenient reach by rotating the body-member on its axis; that the holder is of practical construction in that it allows parts 20 to be readily detached to be cleaned thus making for a sanitary holder of this character.

What is claimed is:

1. A commodity holder including a rotatable body-member embodying an inner series of receptacles and an outer series of receptacles, an upper series of pivoted members and a lower series of pivoted members, a discharge opening at the bottom of each 30 of said receptacles, the upper series of pivoted members being arranged to leave the

openings of the outer series of receptacles obstructed or unobstructed upon movement of the said members, the lower series of pivoted members being arranged to leave the 35 openings of the inner series of receptacles obstructed or unobstructed upon movement of the said members.

2. A commodity container comprising a rotatable body-member embodying attaching members, plates held detachably in place diametrically by said attaching members, the said plates having slots therein, a set of attaching plates each having attaching portions which are insertable in the slots 45 in said first plates, plates concentrically arranged and detachably held in place by said attaching plates, the said diametrically arranged plates and the concentrically arranged plates with the said body-member 50 forming a plurality of receptacles, each of said receptacles having an opening in the bottom thereof, a plurality of pivotally mounted members selectively operable to leave a particular opening of a particular receptacle obstructed or unobstructed, and means for limiting the movements of each 55 of said members.

In testimony whereof I hereby affix my signature.

CHARLES F. SCHLOSSER.
